[57] ABSTRACT

A system to apply a strip to a roller including a shoe movable radially toward the roller in the region where the strip will engage the roller, a jack to move the shoe and means to inject a fluid between the shoe and strip to transfer the force of the jack to the strip while keeping the shoe clear of the strip.

2 Claims, 2 Drawing Figures

FIG:1

FIG:2

SYSTEM FOR DRIVING OR BRAKING A STRIP

During the various stages in the production of a metal strip it is frequently necessary for it to move continuously and for it to be subjected to appropriate traction conditions in various zones for the purposes of the operations that it is required to undergo in such zones.

Means are therefore required to impart these different required traction conditions to the strip.

Such means are generally either driving or braking rollers, around which the strip extends over an angle α , as shown in FIG. 1.

The known formulas indicate the limits in which a roller of this kind can convert a tension t_1 into an outlet tension t_2 .

The following equation applies:

$$t_1 e^{-f\alpha} \leq t_2 \leq t_1 e^{f\alpha}$$

in which f is the coefficient of friction of the strip on the roller and α is the angle by which the strip extends around the roller. The tension increase or reduction capacity is therefore limited by the slip of the strip on the roller.

To increase this drive capacity, it is conventional practice to use pressure rollers which apply the strip against the drive or brake roller.

These pressure rollers have a limited effect, because the force that they exert on the strip must not be such as to result in any deformation of the latter.

They also have the very serious disadvantage of producing faults in the strip guidance, and such faults may be such that the strip leaves its normal path, so that it is then impossible for the production line to continue operating.

To increase this drive capacity, it has also been proposed to exert pressure on the strip in the region in which the said strip is applied to the roller. In the prior art systems, a stationary member is disposed outside the roller and forms a chamber between itself and the roller, a pressure fluid being introduced into said chamber to apply the strip to the roller.

These known systems have the disadvantage of requiring a considerable flow of pressure-transmitting fluid. There is an appreciable clearance between the chamber and the roller over which the strip (of varying thickness) extends.

The object of this invention is to improve these latter known systems.

According to the present invention there is provided a system for driving a strip comprising a roller for receiving strip, a shoe applicable radially toward the roller in the region in which the strip is received, and means to inject a pressure fluid radially inward of said shoe, the system being characterized in that the shoe is slightly movable in a fixed frame by a jack so that when pressure fluid is applied between the shoe and a strip received by the roller, the strip will be applied against the roller with a force equal to that exerted by the jack on the shoe, while contact between the shoe and the

strip will be prevented by the formation of a very thin fluid cushion which will leave only a very small clearance between the shoe and the strip and which will prevent any rubbing of the shoe on the strip.

5 According to a specific feature of the invention, the pressure fluid is compressed air.

It will be apparent that the combination of the effect of the pressure of the jack on the shoe results in a very small flow of pressure fluid between the shoe and the strip and also prevents any rubbing of the shoe on the strip. These two considerable advantages are not found in the prior art systems. In the invention, firstly, the fluid consumption is greatly reduced and, secondly, the disadvantages of the shoe rubbing on the strip are eliminated.

10 One embodiment of the system according to the invention will be explained hereinafter by way of example without limiting force in order that the invention may be more readily understood.

15 FIG. 1 is a diagrammatic end elevation of a roller with a strip applied to it.

FIG. 2 is a vertical section of this embodiment.

20 The strip 1 moves in the direction of the arrow and passes successively around a deflector roller 2, and then a drive (or brake) roller 3 and finally a deflector roller 4. Reference 9 denotes the frame which supports the bearings forming the axes of rotation of the rollers 2, 3 and 4.

25 A shoe 5 is guided in the frame 9 at 10.

30 A jack 7 fed with pressure fluid by the device 8 applies the shoe 5 against the strip 1 in the region where said strip extends around the roller 3. A device 6 feeds compressed air to the cavity of the shoe 5 adjacent the strip.

35 A valve 11 provides a varying pressure loss between the supply 6 and the shoe 5 so that the rate of flow of the fluid can be reduced. Said flow will be adjusted — for a given force of the jack 7 — to a value just sufficient to prevent the shoe 5 from rubbing on the strip.

40 Of course, variants and improvements as to detail, and the use of equivalent means, are possible without departing from the scope of the invention.

I claim:

45 1. A system for driving a strip comprising a roller for receiving a strip, a shoe movable radially toward the roller in the region in which the strip is received, and means for injecting compressed air radially inward of said shoe against said strip, a fixed frame movably supporting said shoe, a jack moving said shoe in said frame whereby when compressed air is applied between said shoe and said strip on said roller, said strip is applied against said roller with a force equal to that exerted by said jack on said shoe, the compressed air forming a very thin fluid cushion and providing a very small clearance between said shoe and said strip preventing rubbing of said shoe on said strip.

50 2. A system according to claim 1, said means for injecting pressure fluid between said shoe and said strip including a valve providing an adjustable pressure loss.
